AUTOMATIC SEQUENTIAL OPERATION TYPE
CLOTHES WASHING MACHINEKenneth O. Sisson, Oakwood, Ohio, assignor to
General Motors Corporation, Dayton, Ohio, a
corporation of Delaware

Application November 4, 1944, Serial No. 561,881

10 Claims. (Cl. 68—12)

1

This invention relates to domestic appliances, and more particularly to washing machines.

An object of this invention is to provide a washing machine of the centrifugal type, and having a door or lid for access thereto, with a safety feature, having an electrical interlock such that filling and agitation can take place whether the door is open or closed; but in which the spinning action can only take place while the door is closed. This allows the user to inspect the interior of the washing compartment during the relatively safe fill and agitation periods, but prevents or stops the relatively dangerous centrifugal action when the door is open.

Another object of this invention is to provide a washing machine of the centrifugal type with a safety feature, such that, when the access door is opened during the centrifugal spin period, such spin period, and the timer control, are arrested until the door is closed, when the spinning action and the timer operation are automatically resumed. This allows the machine to resume its spinning operation after the door is closed to complete the remaining cycle or cycles as if the door had not been opened.

Further objects and advantages of the present invention will be apparent from the following description, reference being had to the accompanying drawings, wherein a preferred form is clearly shown.

In the drawings:

Fig. 1 is a diagrammatic representation of the complete washing machine and its electrical connections with a combined timer and door control;

Fig. 2 is a wiring diagram for the washing machine shown in Fig. 1; and

Fig. 3 is a diagrammatic end view of the control knob for the timer control.

A washing machine, according to my invention, may include a rotatable basket or tub 50, containing an agitator 51. The tub and agitator are operated by a transmission 52 and power motor 53, contained in a unitary casing below the tub 50.

The transmission 52 may be controlled by a solenoid 54 which causes the transmission 52 to produce agitation when the solenoid 54 is not energized and to produce centrifugal rotation when the solenoid is energized. Any transmission of this type may be used.

For example, the tub, agitator, motor, transmission and solenoid may be of the type disclosed in the application of Kendall Clark, S. N. 55 27, 1940, the gears 71 and 72 of my application

2

511,515, filed Nov. 24, 1943 Patent No. 2,422,395 granted June 17, 1947.

The foregoing mechanisms may be enclosed in a cabinet 55, which is provided with an access door 56, which may be opened and closed and which is connected to a door switch 57 which opens and closes at 57a in response to the opening and closing of the door 56, through the medium of rod 58.

10 The tub 50 of the washing machine may be filled by a liquid supply means including a cold water supply line 59 and a hot water supply line 60 and which lead to a thermostatic mixing valve 61 and to liquid operated valve means which may 15 include a mixed or tepid water solenoid valve 62 and a hot water solenoid valve 63. These discharge selectively into a mixing chamber 64 and from thence through a constant pressure reducing means 65 and fixed orifice 66 through the 20 nozzle 67 into the tub 50. This liquid supply means, or liquid feeder, may be substantially as disclosed in the application of Kendall Clark, S. N. 358,871, filed September 28, 1940 Patent No. 2,366,236 granted January 2, 1945. The arrangement 25 is such that a predetermined rate of flow of liquid is provided at nozzle 67, and the timer controls the solenoid 62 or 63 to provide a fixed length of time of discharge at the nozzle, thus discharging a predetermined amount of liquid 30 into tub 50, which fills the tub 50 to the desired level for washing.

The washing machine may be controlled by a combined timer and door switch arrangement, as diagrammatically shown in Fig. 2. This arrangement may include a timer motor 70, which drives a pinion 71 meshed with gear 72. The gear 72 is fixed to an axially movable shaft 73. The shaft 73 may be moved axially by snap action under the control of the lug 74, pushed axially 40 by the spring 74a, selectively in the grooves 75 and 76 in a wheel 77 fixed to the shaft 73, the shaft snapping axially as the lug 74 snaps from one groove to the other. The shaft 73 may be moved axially by the operator through the 45 medium of the knob 78, which may be fixed to the end 79 of the shaft 73, the flat portion 80 on the knob shank fitting with the flat portion 81 of the shaft 73 to prevent relative rotation between the knob 78 and shaft 73. The knob 78 and shaft 73 may be axially secured together by any well known construction such as a radial screw, not shown. The timer 70 preferably operates the pinion 71 by quick equal impulses, as described in the patent to Poole No. 2,191,538, granted Feb. 27, 1940, the gears 71 and 72 of my application

corresponding to gears 29 and 30 in the said Poole patent. Other similar drives are also disclosed in the patents to Poole 2,191,539; 2,191,540 and 2,191,541, which also show how to impart step by step motion to a small pinion, corresponding to my pinion 11. Any of these timer motor constructions may be used in my timer motor casing 70.

The shaft 73 may carry a plurality of cams 82, 83 and 84 which are provided with proper ridges and valleys to operate movable contacts 2, 4 and 7. The shaft 73, when moved axially, also operates an off and on switch 85, which opens when the shaft is pulled towards the operator and is closed when it is pushed away from the operator. The switch 85 is operated from the shaft 73 through the medium of leaf 85a. The knob 78 and shaft 73 are illustrated in the F position, with the shaft 73 pulled out to disconnect all circuits at 85.

Power may be supplied for the washing machine through electric power connectors L₁ and L₂, which may be plugged into any electric power outlet usually found in a residence. Connector L₁ may be connected to one side of the solenoids 84, 82 and 63 and motors 53 and 70. Connector L₂ may be connected to a door switch by-pass contact 12 and to the door switch 87. The door switch opens and closes at 87a as the door 56 is opened and closed. The door switch 87 in turn is connected to the timer door switch contact or connector 1. The safety switch movable contact 2 is operable by the cam 84 to be placed in contact with 1 or 12, or intermediate thereof. The contact 2 carries the L₁ current from either contact 1 or 12 or the "off" and "on" switch 85 and from thence to the line 86. The line 86 is connected to the movable contacts 4 and 7 and to the other terminal of the timer motor 70. The stationary contact 3 is connected to a hot or mixed water selector switch 87 which may be manually selectively connected to the stationary contacts 88 or 89. The contact 88 is connected to the hot water solenoid 63 while the contact 89 is connected to the mixed water solenoid 82. The contact 5 is connected to the transmission solenoid 84. The movable contact 4 is moved by the cam 83 into contact with either 3 or 5 or intermediate thereof. The contact 6 is connected to the mixed solenoid 82 while the contact 8 is connected to the motor 53. The movable contact 7 may be moved into contact with 6 or 8 or intermediate thereof by the cam 82.

When the knob 78 is pulled toward the operator, all circuits are broken at 85 and the machine cannot operate regardless of the turned position of the knob. The operator may therefore stop the machine during any cycle by pulling the knob 78. When the knob 78 is turned to the "off" position A, all circuits are broken at 2, which is then intermediate 1 and 12. This is the automatic "off" which stops the machine when all of the cycles have been finished.

In the operation of the machine, clothes and detergent are introduced into the basket and the knob 78 is pushed in (if out) and turned to the initial position at "fill." This starts the machine and thereafter the timer motor will so actuate the movable contacts 2, 4 and 7 so that the proper amount of hot or tepid water is introduced as selected at switch 87 during fill period D-E; then an agitation action is produced during a "wash" period E-F; and, if the door 56 is in closed position, a spinning action during a "spin" period F-H. Thereafter, a second filling

action is produced during a "fill" period H-I, which may be a hot fill or a mixed fill depending upon the manual selection at switch 87. Thereafter a second agitation during a "rinse" period I-J and second spin, during a "spin" period J-L, are produced. Thereafter a third "fill" period L-M is established which is a mixed water fill (regardless of the position of switch 87), followed by a third agitation or "rinse" period M-N and third spin or "dry" period N-A, after which the operation of the machine is automatically stopped, including the timer motor 70, by the moving of the contact 2 intermediate the contacts 1 and 12 through the medium of cam 84.

The positions of the various contacts during these operations are indicated in Fig. 3 wherein the plus sign is used to indicate the closing of contacts, and the minus sign is used to indicate the opening of contacts. The path of the current during the various periods is as follows: When the user starts to turn the knob from the finish position A, all of the circuits are open by the intermediate position of contact 2 between 1 and 12. As the knob is turned clockwise to B, contact 1 is disconnected from 8 and 4 from 8. Further turning of the knob to C connects 3 and 4. At the start of the first fill position D, contact 2 is moved to 12. This establishes one circuit from L₁, 88, 12, 2, 85, 85a, 86, 4, 3, 81, 87, either 88 or 89 and either 63 or 82 to L₂. This starts the flow of either hot water or mixed water (as selected by the position of 87) into the tub. Another circuit is established from L₁ to 86, as heretofore described, to timer motor 70 and L₂. This starts the timer motor running, and advances the shaft 73, step by step, through the fill period thus filling the tub to the desired level. At the start E of the wash period, contact 4, disconnects from 3 and 7 contacts 8. This breaks the circuit through the water solenoids 63 or 82 and establishes a circuit through the motor 53, the circuit coming from line 86, as previously described, through 7, 8, 82, 53 and L₂. Since the transmission solenoid 84 is not energized, operation of the motor 53 causes the agitator to reciprocate vertically during the wash period. At this time the motor 70 continues to run and advance the shaft 73 throughout the wash period. Should the door 56 be opened during the foregoing fill or wash period, the circuits will not be changed because the opening of door switch 87 does not affect the flow of current from 70 to 12 and 2, through which the current is then passing. As the shaft continues to turn to the first spin period at F, contact 4 is moved to 5 and contact 2 is moved to 1. This causes the current to flow from L₁ through 88, 57, 1, 2, 85, 85a, 86, 4, 5, 83, 84 and L₂. This energizes the transmission solenoid 84. The current also continues to flow from 86 through 7, 8, 82, 53 and L₂. This causes the motor 53 to spin the tub, since the transmission solenoid 84 is energized. The timer motor 70 continues to run, since the current also continues to flow from 86 through 84 to 70 and L₂. Should the door 56 be opened during this spin period all of the circuits are opened by the opening of switch 87 at 87a, since all of the current is now passing through this switch. This will stop the spinning operation, as a brake is automatically applied when the motor 53 is deenergized, as disclosed in the said Clark application S. N. 511,515, or, if the spin has not actually started, then it is prevented from starting by the stopping of the motor 53. Motor 70 also is stopped, and therefore the timer remains in its position as long as the door is

open; but is ready to continue exactly where it left off as soon as the door is closed. At G, just before the timer advances to the second fill period, contact 4 is moved from 5 and 7 from 8. This deenergizes the solenoid 54 and the motor 53 and automatically applies a brake to the spinning basket, stopping it before the second fill is reached at H, as described in the said Clark application S. N. 511,515.

When the timer advances to the second fill position at H, the same circuits are re-established, which were established at the beginning of the first fill at D, and the tub is filled with water (either hot or mixed, as selected at 87) to the desired level while the timer advances through the second fill position. When the timer reaches the first rinse position at I, the same circuits are established which were established during the first wash period at E, and the agitator is vertically reciprocated throughout the rinse period. Should the door be opened during the second fill (H—I) and the first rinse (I—J) period, none of the circuits are interrupted, since the current is passing through contact 12 and the door switch 57 is by-passed, so that it cannot affect any of the circuits. When the timer reaches the second spin position at J, the same circuits are re-established, which were established during the first spin position at F, and the door assumes control of the circuits exactly as it did during the first spin period. At K, just before reaching the third fill period, contact 4 is disconnected from 5 (to its intermediate position) and contact 7 is disconnected from 8 (to its intermediate position), thus automatically applying a brake to the basket and stopping it just before the timer reaches the third fill period at L. When the timer reaches the last fill period at L, contact 2 is moved to contact 12 as in the other fill periods; but the contact 7 is moved to contact 6 while contact 4 remains intermediate contacts 3 and 5. This continues to energize the timer motor 78 and sends current from line 86 through 7, 6, 95 to the mixed solenoid 62, so that the last fill is with mixed water regardless of the position of switch 87. The door does not have control of the circuits during this last fill period. As the timer reaches the last rinse period at M, the circuit to solenoid 62 is broken by moving contact 7 from 6 to 8. This establishes a circuit from 86 through 7, 8, 92 and motor 53 to line L₂. Operation of the motor 53 causes vertical reciprocation of the agitator throughout the rinse period. When the last dry period is reached at N, the same circuits are re-established which were established at the previous spin periods at F and J, and the tub rotates for the final drying of the clothes. At A, the end of the dry period, contact 2 is moved intermediate 1 and 12, thus opening all of the circuits in the machine, and stopping all operations. The clothes, now completely washed and damp dried, may then be removed from the machine. Should the door be opened during the last dry period N—A, the basket is automatically stopped, or prevented from starting, exactly as it was during the previous spin periods. Should the user wish to stop operation of the machine at any time, he merely pulls the knob 78 towards him, as previously described, and thus opens all of the circuits at 85, regardless of any other positions in the circuits. This stops the machine.

While the form of embodiment of the invention as herein disclosed, constitutes a preferred form, it is to be understood that other forms might

be adopted, as may come within the scope of the claims which follow.

What is claimed is as follows:

1. A washing machine comprising: a centrifugally rotatable basket; agitating means for clothes in said basket; a power motor; transmission means to connect said motor to rotate said basket centrifugally and to agitate said clothes; a liquid feeder for said basket; a door for access to said basket; a timer having a fill period, an agitation period, and a spin period; a timer motor; liquid feed solenoid means; an agitation and spin solenoid; a power motor contact; a liquid feed solenoid means contact; an agitation and spin solenoid contact; a door switch placeable in series with said contacts and timer motor and opening and closing with the opening and closing of said door; a door switch contact placeable in series with said door switch, contacts and timer motor; a door switch by-pass contact electrically by-passing said door switch; said timer, during said fill period placing said liquid feed solenoid means contact and timer motor selectively in series with said door switch contact or said door switch by-pass contact; said timer, during said agitation period placing said timer motor and power motor contact selectively in series with said door switch contact or door switch by-pass contact; said timer, during said spin period placing said timer motor, power motor contact and agitation and spin solenoid contact in series with said door switch contact only.

2. A washing machine comprising: a centrifugally rotatable basket; agitating means for clothes in said basket; a power motor; transmission means to connect said motor to rotate said basket centrifugally and to agitate said clothes; a liquid feeder for said basket; a door for access to said basket; a timer having a fill period, an agitation period, and a spin period; a timer motor; liquid feed solenoid means; an agitation and spin solenoid; a power motor contact; a liquid feed solenoid means contact; an agitation and spin solenoid contact; a door switch placeable in series with said contacts and timer motor and opening and closing with the opening and closing of said door; a door switch contact placeable in series with said door switch, contacts and timer motor; a door switch by-pass contact electrically by-passing said door switch; said timer, during said fill period placing said liquid feed solenoid means contact and timer motor selectively in series with said door switch contact or said door switch by-pass contact; said timer, during said agitation period placing said timer motor and power motor contact selectively in series with said door switch contact or door switch by-pass contact; said timer, during said spin period placing said timer motor, power motor contact and agitation and spin solenoid contact in series with said door switch contact only; and an off switch manually operable to open all electrical circuits of said washing machine, and automatically operable to open said circuits upon the termination of said fill period.

3. A washing machine comprising: a centrifugally rotatable basket; agitating means for clothes in said basket; a power motor; transmission means to connect said motor to rotate said basket centrifugally and to agitate said clothes; a liquid feeder for said basket; a door for access to said basket; a timer having a fill period, an agitation period, and a spin period; a timer motor; liquid feed solenoid means; an agitation and spin solenoid; a power motor contact; a liq-

uid feed solenoid means contact; an agitation and spin solenoid contact; a door switch placeable in series with said contacts and timer motor and opening and closing with the opening and closing of said door; a door switch contact placeable in series with said door switch, contacts and timer motor; a door switch by-pass contact electrically by-passing said door switch; said timer, during said fill period placing said liquid feed solenoid means contact and timer motor selectively in series with said door switch contact or said door switch by-pass contact; said timer, during said agitation period placing said timer motor and power motor contact selectively in series with said door switch contact or door switch by-pass contact; said timer, during said spin period placing said timer motor, power motor contact and agitation and spin solenoid contact in series with said door switch contact only; said liquid feed means having hot water and mixed water connections selectively operable by a hot and mixed water switch in series with said liquid feed solenoid means.

4. A washing machine comprising: a centrifugally rotatable basket; agitating means for clothes in said basket; a power motor; transmission means to connect said motor to rotate said basket centrifugally and to agitate said clothes; a liquid feeder for said basket; a door for access to said basket; a timer having a fill period, an agitation period, and a spin period; a timer motor; liquid feed solenoid means; an agitation and spin solenoid; contacts closed by said timer during various of said periods including a power motor contact, a liquid feed solenoid means contact, a spin contact, a timer motor contact; a safety selector movable by said timer; a door switch and a door switch by-pass line selectively placeable in series with said contacts by said selector; said door switch being placed in series with said contacts during said spin period, and said by-pass line being placed in series with said contacts during said fill and agitation periods.

5. A washing machine comprising: a basket; an agitator; a hot water solenoid valve; a tepid water solenoid valve; said valves having liquid feed means into said basket; a power motor, a transmission connecting said motor to said agitator and basket, a spin solenoid energizing said transmission to spin said basket; a door for access to said basket and having a door switch; a by-pass line by-passing said door switch; a timer having a fill period, an agitation period and a spin period; said timer having contacts movable sequentially to open selectively one of said solenoid valves during said fill period, to energize said power motor during said agitation and spin periods and to energize said pin solenoid during said spin period; said timer placing said door switch in series with said contacts during said spin period and placing said by-pass line in series with said contacts during said fill and agitation periods.

6. A washing machine comprising: a basket; an agitator; a liquid feeder for said basket; a liquid feeder electrically controlled valve controlling said liquid feeder; a power motor; a transmission connecting said power motor to said agitator and basket; an electrically controlled transmission controller controlling said transmission to select rotation of said basket and agitation of said agitator; a door for access to said basket; a door switch; a by-pass line and by-pass switch electrically by-passing said door switch;

5 a timer having a fill period, an agitation period and a spin period; said timer having contacts movable to open said liquid feeder electrically controlled valve during said fill period, to energize said power motor and to cause said transmission controller to cause said transmission to agitate said agitator during said agitation period, and to cause said transmission controller to cause said transmission to spin said basket during said spin period; said timer closing said by-pass switch during said fill and agitation periods and opening said by-pass switch during said spin period.

10 7. A control comprising: a timer motor; a power motor; a power motor switch; a spin switch; an agitation switch; a rotatable timer shaft rotated by said timer motor and actuating said switches by rotation of said shaft; a door switch; a safety switch actuated by rotation of said shaft and having a door switch by-pass position and a door switch series position; said safety switch being actuated to said by-pass position when said power motor switch and agitation switches are actuated, and said safety switch being actuated to said series position when said power motor switch and said spin switch are actuated.

15 8. A control comprising: a timer motor; a power motor; a power motor switch; a spin switch; an agitation switch; a rotatable and axially movable timer shaft rotated by said timer motor and actuating said switches by rotation of said shaft; an on and off switch opened and closed by axial movement of said shaft; a door switch; a safety switch actuated by rotation of said shaft and having a door switch by-pass position and a door switch series position; said safety switch being actuated to said by-pass position when said power switch and agitation switches are actuated, and said safety switch being actuated to said series position when said power motor switch and said spin switch are actuated.

20 9. A control comprising: a timer motor; a rotatable timer shaft rotated by said timer motor; 45 switch blade actuating cams on said shaft; switch blades actuated by said cams; a power motor; a power motor switch contact energizable by one of said blades; a spin switch contact energizable by one of said blades; an agitation switch contact energizable by one of said blades; a door switch; a safety switch blade actuated by rotation of said shaft; a door switch series contact in series with said door switch and energizable by said safety switch blade in one position; a door switch by-pass contact by-passing said door switch and energizable by said safety switch blade in another position; said series contact being energized when said power motor switch contact and spin switch contact are energized, and said by-pass contact being energized when said power motor switch contact and agitation switch contact are energized.

25 10. A control comprising: a timer motor; a rotatable and axially movable timer shaft rotated by said timer motor; an on and off switch actuated by axial movement of said timer shaft; switch blade actuating cams on said shaft; switch blades actuated by said cams; a power motor; a power motor switch contact energizable by one of said blades; a spin switch contact energizable by one of said blades; an agitation switch contact energizable by one of said blades; a door switch; a safety switch blade actuated by rotation of said shaft; a door switch series contact in series with said door switch and energizable by said safety

switch blade in one position; a door switch bypass contact by-passing said door switch and energizable by said safety switch blade in another position; said series contact being energized when said power motor switch contact and spin switch contact are energized, and said by-pass contact being energized when said power motor switch contact and agitation switch contact are energized, said on and off switch being in series with said blades and timer motor.

Certificate of Correction

Patent No. 2,520,695

August 29, 1950

KENNETH O. SISSON

It is hereby certified that error appears in the printed specification of the above numbered patent requiring correction as follows:

Column 3, line 36, for the word "or" read *to*; column 7, line 59, for "pin" read *spin*;

and that the said Letters Patent should be read as corrected above, so that the same may conform to the record of the case in the Patent Office.

Signed and sealed this 14th day of November, A. D. 1950.
